UNITED STATES PATENT OFFICE

FREDERICK SCHMIDGALL, OF CINCINNATI, OHIO

DOORLATCH

Application filed December 19, 1932. Serial No. 647,933.

My invention relates to door latches particularly applicable to so-called refrigerator doors, and it is the object of my invention to provide certain new and useful improvements in latches of this character.

It is the object of my invention to provide a novel latch comprising a bolt-slide having a guided barrel in which there is an actuating spring, and novel means for adjusting the spring; further, to provide novel actuating means for the bolt; further, to provide novel means for initiating opening movement of the door; and, further, to provide novel means acted on by the spring of the latch for urging closing of the door.

The invention will be further readily understood from the following description and claims, and from the drawings, in which latter:

Fig. 1 is a side elevation of my improved device, viewed from the inside of the refrigerator, and partly broken away.

Fig. 2 is a horizontal section of the same in the plane of the line 2—2 of Fig. 1, and partly broken away, and showing the door in closed relation in full lines and in open relation in dotted lines.

Fig. 3 is a cross-section of a detail, taken on the line 3—3 of Fig. 1.

Fig. 4 is an axial section of my improved device, taken in the plane of the line 4—4 of Fig. 1.

Fig. 5 is an end elevation of my improved latch, partly in section on the line 5—5 of Fig. 1, and partly broken away.

Fig. 6 is a cross-section of my improved device, taken on the line 6—6 of Fig. 1, and partly broken away.

Fig. 7 is a cross-sectional detail of my improved device, taken on the line 7—7 of Fig. 1, partly broken away, and showing the releasing members in coacting relation for initiating opening movement of the door.

Fig. 8 is an enlarged side elevation of the inner end of my improved latch, viewed from the bottom of the latch, and partly broken away.

Fig. 9 is a cross-section of the same, taken on the irregular line 9—9 of Fig. 8.

Fig. 10 is a front elevation of a detail of

my improved device, showing the latch in locked relation, and partly broken away.

Fig. 11 is a cross-section of the same, taken on the line 11—11 of Fig. 10.

Fig. 12 is a side elevation, partly in section and partly broken away, showing a modification of the bolt end of my improved device.

Fig. 13 is a side elevation of a further modification of my improved device, showing a plurality of connected bolts, and partly broken away.

Fig. 14 is an end elevation of this modification, partly broken away, and partly in section on the line 14—14 of Fig. 13; and,

Fig. 15 is a cross-sectional detail of the same, taken on the line 15—15 of Fig. 13.

The body of the refrigerator is shown at 21, and has a wall 22 about a door opening 23, arranged to be closed by a refrigerator door 24, supported on hinges 25 from the wall. 70 The wall of the door opening is provided with an inclined seat 26, in which the slanting edge faces 27 of the door are received. A seating strip 28 is secured about the wall of the door opening and forms a seat having a 75 cushion 29 thereon. A cushion 30 on the door surrounds the door between a laterally extending flange 31 extending around the outer margin of the door and the margin of the wall. These cushions are compressed when 80 the door is closed for forming a substantially hermetic seal between the wall of the door opening and the door when the door is closed.

A latch 35 is arranged to maintain the door 85 closed. This latch comprises a bottom plate 36. (Figs. 4, 5 and 6.) Guides 37 are secured to this plate, as by means of the screws 38, which pass through holes in said guides and the plate and are screwed into the door. 90 (Fig. 3.) A bolt slide 39 is slideable in guideways 40 in the guides 37, and is provided with a seat 41, in which a tube 42 is fixed, there being a spiral spring 43 in this tube or barrel.

There is a resistance plate 46 at the inner end of the plate, from which a resistance bracket 47 extends. (Figs. 4, 5, 8 and 9.) This plate and bracket are secured to the door by means of screws 48, which pass through holes in said plate and slots 49 in the bottom 100

plate 36, and are threaded into the door. Screws 50 pass through slots 51 in the bottom plate 36 and through holes in the resistance plate, nuts 52 being threaded over said screws for clamping the bracket in adjusted positions to the plate 36.

The bracket is located in a slot 53 in the tube 42 and is provided with a resistance pad 54 in the tube against which one end of the spring 10 is received.

Outward movement of the slide 39 is limited by a shoulder 57 on the plate 36, with which a shoulder 58 on said slide engages, forming stops, for limiting outward movement of the slide.

The plate 36 is located in rabbets 59 in the guides 37 and in a bottom groove 60 in the resistance plate 46 for readily assembling the parts in alignment.

Movement of the slide is further guided by having the tube or barrel guided by the pad 54 in the inside of the barrel and the bracket 47 in the slot 53.

Each of the guides is provided with a wing 25 64 in which there is a hole 65 having an annular shoulder 66 therein. (Figs. 1 and 6.) A hub 67 of an operating arm 68 is received in one of these holes. A rock-shaft 69 is in this hub at one side of the door, exemplified as the 30 inside, and in a reversely placed hub 70 rotatable in a hole 71, in which there is an annular shoulder 72 of an escutcheon plate 73 fixed, as by screws 74, to the other side of the door, exemplified as the outside of the door. The hub 70 has a handle 75 thereon.

A wedge-piece 78 is also secured to the rock-shaft, the wedge-piece being exemplified as having two wedges 79, 80, thereon. The wedge-piece and the hubs are respectively secured to the rock-shaft by pins 81, 82 and 83, and the rock-shaft and the walls of the holes in the wedge-piece and hubs in which it is received may be polygonal in cross-section to aid in preventing relative rotation between 45 said parts.

A keeper 85 having inclined faces 86, 87, thereon, is fixed to the wall of the door opening, as by screws 89 in cheeks 88 of said keeper. (Figs. 1 and 4.) The keeper is located in 50 an interruption 90 of the sealing strip 28.

The bolt-slide 39 comprises a bolt 91 which co-operates with the keeper. This bolt is in Figs. 1, 2 and 4 exemplified as comprising a roller 92 on a pin 93, the outer ends of which 55 are received in bearings of a fork 94 extending from the slide 39, the roller being rotatable and being movable along the inclined face 86 for retracting the bolt when closing the door, the spring urging the roller outwardly along the face 87 when the door is being closed for causing intimate sealing connection between the door and the wall of the door opening, due to the pressure exerted on the bolt and its slide by the spring 43.

65 The bolt is in Fig. 12 exemplified as hav-

ing a nose 95, having inclined faces 96, 97, coacting respectively with the inclined faces 87, 86, on the keeper, for urging the bolt inwardly by coaction of its inclined face 97 with the inclined face 86 of the keeper when closing the door, and having its inclined face 96 coact with the inclined face 87 of the keeper, urged by the spring 43, when the door is being closed, for urging the door into sealing position.

The arm 68 engages a lug 98 on the slide 39 for moving the slide and its bolt inwardly against the resistance of the spring 43 upon operation of either arm 68 or 75 when opening the door. (Fig. 4.)

If it is desired to lock the bolt, a padlock 101 is employed, (Figs. 10 and 11), the bow 102 of which is received through a hole 103 in a tail 104 of the arm 75, the bow when in such relation being received in a slot 105 between lugs 106 extending from the escutcheon plate 73. In case of any one being locked in the refrigerator, he may release himself by removing the pins 81, 82, and pushing the rock-shaft 69 outwardly to sufficient extent 90 to remove the bow 102 out of range of the lugs 106.

One of the wedges 79, 80, is arranged to coact with a wedge-block 111 secured to the wall of the door opening, as on the sealing strip 28, and provided with a wedge-face 112, with which the wedge-face of the last-named wedge coacts when either handle is rocked, for causing the wedge-face on the wedge-arm being rocked to move into range with and 100 against the wedge-face on the wedge-block, resulting in wedging the swinging end of the door outwardly and initiating opening movement of the door, so that the door may be readily opened if the door should be wedged 105 or stuck in its opening or the beginning of its opening movement be otherwise difficult.

The arms 68 and 75 are preferably respectively provided with bend 114, extending away from the door to form handles for being readily grasped by the hand of the operator when opening or closing the door.

The arm 68 is also preferably connected with the hinge side of the wall of the door opening for urging movement of the door in closing direction by the action of the spring 43. (Figs. 1, 2 and 5.) This connection is shown as a flexible connection 117, for instance, a cable. This arm has an inwardly extending bracket 118 provided with an eye 119, in which one end of the flexible connection is secured, the other end of the flexible connection being secured in an eye 120 secured to the sealing strip 28. The purpose of this connection is to normally urge the door into closing relation by the action of the spring 43, employed also in urging the bolt of the latch into latching relation.

It will be noted that the latch and its operating means, as well as its connection with 130

the wall of the door opening, are located at the inside of the door, with the exception of the outer arm or handle 75 and its escutcheon plate, so that only these latter parts and their immediate connections are visible from the outside of the refrigerator, presenting a neat appearance and permitting the operating parts of the latch mechanism to be made very substantial, and avoiding the necessity of highly finishing the same, which results in economy of manufacture. The placing of the operated parts on the inside of the door also removes them from ready access for felonious attack.

15 My improved device may be readily placed at either side of the door, and is exemplified as placed at the right-hand side of the door, looking from the outside of the door. If the door is hinged to swing in the opposite direction, the device may be placed at the opposite side of the door, with the rocker rod in the opposite hole 65 of the guides, and the opposite wedge 80 of the pair of wedge arms being in operative position to coact with the wedge 25 block 111 placed on the opposite side of the wall of the door opening.

If it is desired to adjust the tension of the spring 43, the screws 48 are removed and the nuts 52 relieved from clamping action upon 30 the bracket-plate 46. The bracket 47 is then moved in axial direction with relation to the spring for adjusting the spring, the screws 50 being movable in the slots 51. The nuts 52 are then clamped for securing the bracket in 35 adjusted position. The screws 48 are also screwed into the door in new positions, according to the new position of the bracket, for again securing the parts to the door, the screws 48 passing through the slots 49 in the 40 plate 36 at another position in said slots.

In the modification shown in Figs. 13, 14 and 15, two bolts are exemplified for latching the door. Such an arrangement is desirable where very heavy or very large doors are employed. In this modification, corresponding parts are identified by similar but primed reference numerals.

Both latches are exemplified as operated by the same handle. A handle arm 125 is located at the inside of the door, and a handle arm 126 is located at the outside of the door. Escutcheon plates 127, 128, are respectively secured at the inside and at the outside of the door, and have bearings 129, 130, therein, 55 for receiving the journal portions 131, 132, of the hubs 133, 134, of said handle arms, the hubs being fixed to the rock-shaft.

Arms 137, 138 extend from the respective latches 139, 140, and coact with the lugs on 60 the slides supporting the bolts thereof.

These arms have slot and pin articulations 141, 142, with oppositely extending wings 143, 144, of the guides of the respective latches. These arms extend toward each 65 other and have pivot connection 148 between

them. A link 149 is pivoted to one of these arms, as at 150, at one end of said link, the other end of the link being pivoted, as at 151, to the operating arm 125.

The actuation of either arm 125 or 126 causes swinging of the inner ends of the arms 137, 138, and consequent movement of the bolts of the separated latches in corresponding directions for moving said bolts into latching or into unlatching relations.

A locking arrangement similar to the padlock 101 and its connections may be provided for the outer handle 126.

One of the arms 137, 138, may also be connected with the wall of the door opening for normally urging closing movement of the door by the action of the springs in the respective latches. Such a connection is shown by the flexible connection 117', secured to the arm 137 at one of its ends and to the wall of the door opening at the other of its ends.

Having thus fully described my invention, what I claim as new and desire to secure by Letters Patent, is:

1. In a door latch, the combination with a door and the wall of a door opening, of a bolt-slide comprising a bolt, a keeper for said bolt, a spring normally urging said bolt and said bolt-slide into latching relation with said keeper, a pivoted operating arm having a pivotal axis substantially at right angles to the plane of said door and having operative connection with said bolt-slide to move the latter, said pivoted arm pivoted at one side of said bolt-slide, hinging means between said door and said wall having pivotal axes at one side of said door, and a tension connection between said operating arm and said wall at the other side of said door.

2. In a door latch, the combination with a door and the wall of a door opening, of a bolt-slide comprising a bolt, a keeper for said bolt, a spring normally urging said bolt and said bolt-slide into latching relation with said keeper, a pivoted operating arm having a pivotal axis substantially at right angles to the plane of said door and extending cross-wise of said bolt-slide and having operative connection with said bolt-slide to move the latter, said pivoted arm pivoted at one side of said bolt-slide, said bolt-slide and its bolt, said spring and said operating arm located at the inner face of said door, hinging means between said door and said wall having pivotal axes at the outside of said door, and a tension connection between said operating arm and said wall at the inside of said door arranged to operate said arm upon opening said door and to act on said spring for building up power therein to automatically swing said door in closing direction upon release of said door.

3. In a door latch, the combination with a door and the wall of a door opening, of a bolt-slide comprising a bolt, a keeper there-

- for, a spring normally urging said bolt and said bolt-slide in latching direction, a pivoted operating arm having a pivotal axis substantially at right angles to the plane of said door at the side of said bolt-slide, a wedge-arm movable with said operating arm, and a wedge-block co-operating therewith, said wedge-arm and said wedge-block respectively on said door and said wall and provided with coacting wedge-faces in coacting relation to wedge said door in opening direction upon opening movement of said operating arm.
4. In a door latch, the combination with a door and the wall of a door opening, of a bolt, an operating arm having operative connection with said bolt to move said bolt, hinging means between said door and said wall having pivotal axes at the outside of said door, a tensile connection between said operating arm and said wall at the inside of said door, and a spring to move said bolt and said arm in latching direction and acting on said tensile connection whereby to automatically swing said door in closing direction upon release of said door in open relation.
5. In combination, with a door and the wall of a door opening, of a pair of spaced-apart latches respectively comprising guides provided with oppositely extending wings, bolt-slides guided by said guides, oppositely extending operating arms pivoted to said respective wings, said operating arms extending toward each other and being interpivoted, said operating arms having operative connections with said respective bolt-slides, a pivoted handle at the side of said operating arms, a connecting link between said handle and said operating arms and having pivotal connections with the same respectively, the pivotal axes of said parts being normally substantially parallel and at right angles to the plane of said door, and keepers for said respective bolt-slides.
6. In combination, with a door and the wall of a door opening, of a pair of spaced-apart latches respectively comprising guides provided with oppositely extending wings, bolt-slides guided by said guides, oppositely extending operating arms pivoted to said respective wings, said operating arms extending toward each other and being interpivoted, said operating arms having operative connections with said respective bolt-slides, a pivoted handle at the side of said operating arms, a connecting link between said handle and said operating arms and having pivotal connections with the same respectively, the pivotal axes of said parts being normally substantially parallel and at right angles to the plane of said door, keepers for said respective bolt-slides, said parts located at the inner face of said door, hinging means between said door and said wall having pivotal axes at the outer face of said door, and tension means at the inner face of said door between said operating arms and said wall arranged to build up power in said springs upon opening of said door and automatically moving said door in closing direction upon release of said door.
7. In a door latch, the combination of a guide provided with oppositely extending ears and intermediate guide faces, a bolt-slide guided by said guide faces, a spring normally urging said bolt-slide in latching direction, an operating arm for said bolt-slide arranged to extend transverse to said bolt-slide, said operating arm and each of said ears provided with pivot means whereby to pivot said operating arm selectively to said respective ears with said operating arm selectively extending in each of opposite directions when respectively pivoted to said respective ears.
8. In a door latch, the combination of a guide provided with oppositely extending ears and intermediate guide faces, a bolt-slide guided by said guide faces, a spring normally urging said bolt-slide in latching direction, an operating arm for said bolt-slide arranged to extend transverse to said bolt-slide, said operating arm and each of said ears provided with pivot means whereby to pivot said operating arm selectively to said respective ears with said operating arm selectively extending in each of opposite directions when respectively pivoted to said respective ears a wedge-part operable with said operating arm, said wedge-part having oppositely extending wedge-faces, and a wedge-block with which each of said respective wedge-faces are arranged to co-operate in said respective selective arrangements of said operating arm, and arranged whereby said latch and said wedge-parts may be selectively placed at opposite lateral margins of said door.
9. In a door latch, the combination with a door and the wall of a door opening, of a bolt-slide comprising a bolt and provided with a barrel, a spring in said barrel normally urging said bolt and said bolt-slide in latching direction, guiding means for said bolt-slide under said barrel, a pivoted operating arm pivoted at one side of said bolt-slide and extending between said bolt-slide and said barrel, and a keeper having reversely inclined contact faces contacted by said bolt of said bolt-slide, one of said contact faces arranged to urge said bolt-slide in unlatching direction, and said bolt arranged to be urged along the other of said contact faces by said spring for moving said door into closed relation.
10. In a door latch, the combination of a bottom plate, a guide fixed with relation to said bottom plate at one end of said bottom plate, a bolt-slide guided by said guide, a stop between said bottom plate and said bolt-slide limiting movement of said bolt-slide in latching direction, a barrel extending from

said bolt-slide lengthwise of said guide, a helical spring in said barrel, a resistance part at the other end of said bottom plate, and adjusting means between said resistance part and said bottom plate whereby to adjust the tension of said spring.

11. In a door latch, the combination of a bottom plate, a guide fixed with relation to said bottom plate at one end of said bottom plate, a bolt-slide guided by said guide, a stop for said bolt-slide limiting movement of said bolt-slide in latching direction, a barrel extending from said bolt-slide lengthwise of said guide, a helical spring in said barrel, a resistance part at the other end of said bottom plate, adjusting means between said resistance part and said bottom plate whereby to adjust the tension of said spring, said guide provided with a laterally extending wing, an operating arm for said bolt-slide having pivotal connection with said wing and extending therefrom between said slide and said barrel, and connecting means between said operating arm and said bolt-slide.

25 12. In a door latch, the combination of a bottom plate, opposite guide-pieces provided with oppositely extending wings, means fixing said guide-pieces in opposite relations to opposite sides of one end of said bottom plate to form an intermediate guide extending lengthwise of said bottom plate, a bolt-slide slidable in said guide, stops between said bottom plate and said bolt-slide limiting movement of said bolt-slide in latching direction, 30 a barrel extending rearwardly from said bolt-slide above said guide, said bolt-slide provided with an operating lug, an operating arm therefor, pivoting means between said operating arm and each of said wings, said operating arm extending between said bolt-slide and said barrel, and a resistance part for the other end of said helical spring having connection with the other end of said bottom plate.

In testimony whereof, I have hereunto
45 signed my name.

FREDERICK SCHMIDGALL.
